UNITED STATES PATENT OFFICE.

MORRELL M. LOONEY, OF LA CROSSE, WISCONSIN.

DEVICE FOR CLEANING OUT CHANNELS.

SPECIFICATION forming part of Letters Patent No. 545,602, dated September 3, 1895.

Application filed May 16, 1895. Serial No. 549,423. (No model.)

To all whom it may concern:

Be it known that I, MORRELL M. LOONEY, a citizen of the United States, residing at La Crosse, in the county of La Crosse and State of Wisconsin, have invented new and useful Improvements in Devices for Cleaning out Channels, of which the following is a specification.

This invention relates to improvements in devices for deepening and straightening navigable streams.

The special object of the invention is to so direct the flowage of a stream that the current is concentrated and turned toward a portion of the river so that its bed is scoured and washed out, thus deepening the channel and straightening it, as may be desired, without obstructing navigation during the operation. This result is attained by the use of a pair of barges anchored in the river, with accompanying details, as described in the following specification, reference being made to the accompanying drawings, in which—

Figure 1 is a perspective view of the barge. Fig. 2 illustrates the arrangement of the barges with respect to each other and to the current to get the desired results. Fig. 3 is a cross-section of the barge with the apron and spud raised. Fig. 4 is a cross-section of the barge anchored by the spud, the apron being set down into place as in use. Fig. 5 is a perspective view of a portion of the apron, showing the guide and stiffener and friction-rollers. Fig. 6 is a perspective view of a part of the barge with guide-posts and pulley and the guide.

Similar letters refer to similar parts throughout the several parts.

In Fig. 1, *a* represents the barge, and *b* an iron apron suspended by ropes or chains *c* running over the pulleys *d* in the guide-posts *e*. This iron apron is raised or lowered by means of the crabs or winches *f*. The fins *g* are hinged to the side of the barge which is opposite the iron apron, so that they are almost entirely submerged in the water and are controlled by the chain *h* running to the crab *k*. When not in use, these fins are swung back against the side of the barge.

The spuds *l* are used to anchor and hold the barge in place in the center of the river. They are raised and lowered by means of pinions *m* in the crabs *m*, working into rack-

bars *n*, which are securely bolted to the spuds *l*. When it is desired to anchor the barge, the spuds are lowered until they reach the bottom of the river, when the motion is continued by means of the crabs *m*, which has a tendency to raise the barge upward, but by reason of its weight it only drives the spuds into the bed of the river, thus holding the barge securely in place.

Fig. 4 shows the spud as it is when set into the bottom of the river.

Fig. 6 shows a wrought-iron guide *r*, bolted to the side of the barge, through which the guide *p* on the apron slides, and which assists in holding the apron in its proper position and guides it as it is raised and lowered. The friction-rollers *o o* (shown in Fig. 5) not only hold the apron against the guide-posts, but help the motion of the apron by reducing the friction as it slides up and down.

The method of operation is as follows: The barges, two in number, or more, if necessary, are towed to a point in the river just above and adjacent to the place which is to be scoured and deepened. They are anchored by means of the spuds at the upper ends of the barges, so that they hang downstream parallel to and opposite each other the desired distance apart, as shown by the dotted rectangles *A A* in Fig. 2. The two remaining spuds on each barge are raised and free from the river-bed. The fins *g* are then thrown out across the current by means of the crabs *k*. The current striking against these fins swings the lower ends of the barges toward each other around the upper spud in each barge, which is driven into the bed of the river and holds the barges fast against the current. When the lower ends of the barges have swung sufficiently near each other, so that they are only about one-half as far apart as at the upper ends, then the spuds at the lower ends and in the middle are lowered and forced into the bottom of the river, holding the barges firmly in place, so that they lay diagonally across the current, as shown in Fig. 2 by *B B*. When this has been done, the aprons *b* are released and dropped, so that their lower edges sink into the bottom of the river and shut off the free flowage of the stream, forming the sides of a sluiceway, which, acting like a funnel, concentrates and hastens the

current, so that it scours and washes before it the soil in the bed of the stream which is just below the mouth of the sluiceway thus formed.

5 These barges can be moved out of the way of navigation very quickly and be easily replaced, so that they would not be called an obstruction, as will be obvious.

What I claim is—

10 The combination of the barges *a*, the iron aprons *b*, and the fins *g* carried by said barges, and crabs *f* connected to and operating said

aprons, and spuds *l* connected to and operated by the crabs *m* and the crab *k* connected to and operating the fins, substantially as described.

In testimony whereof I have hereunto set my hand in presence of two subscribing witnesses.

MORRELL M. LOONEY.
